ABSTRACT OF THE DISCLOSURE

An arc plasma generator comprising an arcing passage in which the column of an electric arc is located. The arcing passage is lined with insulating material that evolves gas when heated by the arc. These gases are converted by the high temperature arc into a hot arc plasma that is expelled from the arcing passage through an exhaust passage located intermediate the ends of the arc column. Scavenging means substantially prevents electrode vapors from entering the plasma flowing toward the exhaust passage.

This invention relates to an arc plasma generator and, more particularly, to an arc plasma generator of a simple construction that is capable of producing a highly stable, extremely hot arc plasma that is substantially uncontaminated by electrode decomposition products.

The usual arc plasma generator comprises a pair of spaced-apart electrodes, means for establishing an electric arc in a suitable arcing passageway extending between the electrodes, and means for sending through the arcing passageway a stream of gas that is heated by the arc and exhausted through a suitable exhaust port. The highly-heated gas is referred to as an arc plasma.

Typically, the walls of the arcing passage are made of metal sections spaced apart along the length of the passage and insulated from each other. In such constructions it is necessary to provide the metal sections with special cooling means to prevent the metal walls from being vaporized by the arc so as to prevent any such metal vapors from entering and contaminating the plasma. Such cooling means for the wall is usually quite involved and expensive. Another feature that has made many prior arc plasma generators unduly expensive and complicated is that the arc plasma has been created by feeding the arc with a stream of gas introduced from a source outside the arcing passageway. In addition, the stream has typically been introduced at a plurality of points, thus further complicating the device.

A plasma generator that embodies the above described features is shown and claimed in U.S. Patent No. 3,146,371 McGinn, assigned to the assignee of the present invention. Another feature of this plasma generator is that a portion of the gas stream introduced from the external source is used for producing a scavenging action that blocks entry of the electrode decomposition products into the plasma stream that is flowing toward the exhaust port. This blocking action greatly reduces contamination of the plasma by electrode decomposition products, but it also involves the complication of requiring an external source for the scavenging gases.

An object of the present invention is to provide an arc plasma generator of a simple construction that can provide an extremely hot arc plasma free from electrode vapors without requiring an external source of gas either for feeding the arc or for scavenging purposes.

Another object is to construct the arc plasma generator in such a manner that the arc plasma exhaust has a high degree of freedom from fluctuations in temperature and velocity.

In carrying out the invention in one form, we provide

a pair of electrodes between which an arc is adapted to be established. Means defining an arcing passage that extends between the electrodes is provided for receiving the column of the arc. The arcing passage is lined with insulating material that is directly exposed to the arc and is adapted to evolve gases when heated by the arc. These gases are heated to a high temperature by the arc. Extending transversely of the arcing passage at a location intermediate the electrodes is an exhaust passage. Means is provided for forcing most of the gas evolved from the insulating material to flow along said arcing passage toward said exhaust passage and then out through the exhaust passage. Scavenging means is provided for substantially preventing the vapors evolved from each of said electrodes by said arc from entering the stream of gases flowing toward the exhaust passage. This scavenging means comprises means for causing a minor portion of the gases evolved from said insulating material by the arc to flow past each of the electrodes in a direction leading away from said exhaust passage.

For a better understanding of our invention, reference may be had to the following description taken in conjunction with the accompanying drawings, wherein:

FIG. 1 is a cross sectional view showing an arc plasma generator embodying one form of our invention.

FIG. 2 is an enlarged cross sectional view of a portion of FIG. 1.

FIG. 3 is a view taken along the line 3—3 of FIG. 1.

FIG. 4 illustrates a modified form of the invention viewed along a line such as line 3—3 of FIG. 1.

Referring now to FIG. 1, there is shown an arc plasma generator 10 that comprises a pair of tubular electrodes 12 between which an electric arc 14 is adapted to be formed. Each of the electrodes 12 is preferably formed of graphite, which is a material having a low rate of arc-erosion. Positioned between the electrodes 12 is a block 16 of insulating material having an arcing passage 18 extending therethrough between the electrodes 12. The arcing passage 18 is lined with a tubular liner 20 of insulating material. This liner is directly exposed to the arc 14 and is adapted to evolve gases when heated by the arc.

An exhaust port or passage 22 is shown extending transversely of the arcing passage 18 and communicating therewith at a location approximately midway between the two electrodes 12. The transversely-extending exhaust port 22 is also provided with a liner 24, preferably of the same insulating material as the liner 20.

Surrounding each of the tubular electrodes 12 is a cylindrical heat sink 26 of a highly conductive metal such as copper. Preferably, each electrode is press fitted into its surrounding heat sink 26. Each of the illustrated heat sinks 26 comprises two cylindrical members 30 and 32. The cylindrical members are suitably secured to the insulating block 30, as by means of screws 34 extending through aligned openings in these parts and threaded into the block 30. The heat sink members 30 and 32 are respectively formed with internal annular shoulders 40 and 42 that are positioned at opposite ends of the associated electrode 12. These shoulders 40 and 42 confine the electrode 12 against axial movement.

Each heat sink 26 is capable of quickly absorbing large amounts of heat from its associated electrode member 12, thus helping to limit the temperature of the electrode member. By limiting the temperature of the electrode member 12, the heat sink 26 prevents the adjacent insulating block 16 from becoming overheated and damaged by the temperature rise of the electrode member. Added protection for insulating block 16 is provided by the shoulder 40 on the heat sink 26. This shoulder 40, which is interposed between the electrode member 12 and the insulating block 16, acts as a heat shield for reducing the

effective exposure of insulating block 16 to the hot electrode member 12.

Still further, each heat sink serves as an electric terminal for the plasma generator. In this latter regard, the leads 44 from an external electrical power source are bolted to the heat sinks 26. Electric current can flow through the copper heat sinks 26 between the associated electrode 12 and the associated lead 44.

The arc 14 between the electrodes 12 is normally started by relying upon a thin striking wire (not shown) connected between the electrodes. A high energy source of electric current (not shown) is connected across the leads 44 causing a high current to traverse the striking wire. This high current causes the striking wire to immediately vaporize, thereby establishing the arc 14 between the electrodes 12. The arc terminals are schematically indicated in FIG. 1 as attaching to the cylindrical electrodes 12 about substantially their entire inner periphery. The column of the arc 14 extends between the electrodes 12 through the arcing passage 18.

The intense heat of the arc immediately vaporizes a portion of the insulating material forming the liner 20. The resulting gases are quickly heated by the arc to a very high temperature to form an arc plasma, and most of this arc plasma is driven at high speed along the arcing passage 18 toward the exhaust port 22. The arc plasma is expelled through the exhaust port 22 at high speed to form the arc plasma jet indicated at 50.

For forcing most of the arc plasma to follow the above-described flow path, i.e., along the arcing passage 18 toward the central exhaust port 22 and then out through the exhaust port, we provide plugs 52 at the outer end of each cylindrical electrode 12. Each of these plugs 52 presents a relatively high impedance to the flow of arc plasma in an axially outward direction, and thus most of the plasma flows in an opposite direction, i.e., toward the low impedance exhaust port 22.

For maintaining the main arc plasma jet 50 substantially free of contamination from electrode decomposition products, we provide a small venting passage 54 extending through each of the end plugs 52. A minor portion of the arc plasma developed by the arc decomposing the insulating liner 20 is vented through each of these passages 54 via a path that extends axially outward through the bore of the cylindrical electrode 12. This minor flow of the arc plasma carries with it electrode decomposition products, thus performing a scavenging action which substantially prevents the electrode decomposition products, or electrode vapors, from entering the stream of arc plasma flowing toward the central exhaust port 22.

The following is a more detailed explanation of the manner in which this scavenging of the electrode vapors is believed to occur. The arc terminal at each electrode heats the inner periphery of the electrode 12 to a very high temperature, vaporizing some of the electrode material, and producing high speed jets of vaporized electrode material that project away from the hot electrode surface. These jets of electrode vapor, which are schematically depicted at 56 in FIG. 2, tend to leave the electrode surface generally normal thereto. Because the surface on which each arc terminal is rooted is the inner peripheral surface of the electrode 12, the jets tend to leave the electrode surface generally normal to the column of the arc. This is advantageous because a jet projecting in this generally normal direction is less likely than a downstream-projecting jet to carry electrode vapors into the stream of plasma that is flowing through the arcing passage 18 toward the exhaust port 22. Instead of projecting electrode vapors far downstream into the column region of the arc, as would be the case with downstream-directed jets, these normally directed jets tend to bounce their electrode vapors off the opposed inner peripheral wall of the electrode 12. To some extent, this tends to confine and collect these electrode vapors inside the bore of the cylindrical electrode 12.

When collected in this manner, the electrode vapors can be more easily swept from the arcing passage 18 by the minor flow of arc plasma out the venting passage 54. This permits us to rely upon a relatively small flow of the useful plasma through the venting passage 54 for effecting the desired scavenging. Being able to limit this flow through venting passage 54 to a low value is highly desirable, since this particular flow represents energy lost and not imparted to the main jet 50.

10 The amount of gas used for such scavenging can be controlled by controlling the cross-section of the passage 54. We prefer to make these venting passages 54 just large enough to provide a flow therethrough that removes substantially all of the electrode vapors. This size can be determined experimentally by spectrographically analyzing the main jet for electrode vapors. The size of the venting passage 54 is increased until the spectrographic analyzer shows a negligible amount of electrode vapors in the main jet.

20 There are several related features which contribute to the high efficiency of our scavenging action. One is that we seal the arcing passage in the region 60 immediately ahead of the electrode 12 and thus prevent any of the hot gases from exhausting transversely of the arcing passage 18 in this region. Any gases generated in this region that do not enter the main plasma stream are forced to follow a path through the cylindrical electrode 12 and out of the passage 54, which is the path for most effective scavenging, as was described hereinabove.

30 This seal in the region 60 is formed by the shoulder 40 on the heat sink 26 and the close fit that it makes with adjacent parts. In this respect, the shoulder 40 has a planar downstream face 63, and the screws 34 clamp this face 63 tightly against the planar face of insulating block 16, thereby preventing any leakage in a radial direction along this downstream face 63. The upstream face of shoulder 40 is also planar, and the electrode member 12 is clamped against this face by the plug 52. This plug 52 is threaded into the outer shoulder 42 on the heat sink 26 until it forces the planar downstream surface 64 of the electrode 12 into engagement with the planar upstream surface of shoulder 40.

40 Another feature that contributes to our high-efficiency scavenging is that our electrode configuration causes the arc terminal to be generally confined to the inner periphery of the tubular electrode 12. Accordingly, the electrode vapor jets are mostly directed radially inward of this surface as was described hereinabove.

45 The arc terminal does not attach to the exposed surface of shoulder 40 because this surface is slightly recessed with respect to the arcing passage 18 and also because the gas evolved by the immediately-adjacent portion of the insulating liner 20 develops a slight radially-inwardly acting force that inhibits the arc terminal from entering this region. The fact that the shoulder 40 and the recess 65 are quite thin, considered longitudinally of the arcing passage 18, also inhibits the arc terminal from entering this region. For these same reasons, the arc terminal is normally prevented from attaching to the downstream surface 64 of the electrode 12.

50 It will be apparent that our scavenging action is obtained in a very simple manner and without the need of any gas derived from an outside source. All of the scavenging gas is obtained from decomposition of the insulating liner 20 by the arc.

55 The gas for the main jet 50 is likewise derived entirely from decomposition of the insulating liner 20. There is no need to rely on any outside source for this gas. This feature contributes materially to the simplicity and low cost of our arc plasma generator. Another advantage of feeding the arc with wall decomposition products is that we are able to obtain considerably higher temperatures for our plasma jet than can be obtained with the usual plasma generator fed with gas from an outside source. 60 In this regard, our studies indicate that we can obtain

temperatures in the range of 30,000 to 50,000 degrees K. A typical maximum temperature range for a plasma generator with metal walls and an outside gas source is about 15,000 to 20,000 degrees K.

One factor that enables us to obtain these very high temperatures is that we can keep the cross-section of our arcing passage 18 very small. Generally speaking and within limits, the smaller this cross-section, the higher the temperatures obtainable. In the type of plasma generator that has metal walls, the metal of the walls vaporizes when the cross-section of the arcing passage is reduced to the small values that we may be concerned with, and these metal vapors contaminate the arc plasma. Thus, to avoid such contamination, relatively large cross-section arc passages must be used with plasma generators of the metal-wall type.

In one specific embodiment of our invention, our arcing passage has a $\frac{3}{8}$ inch diameter and a 4 inch length and has been lined with a liner 20 of methyl methacrylate. Power inputs into this generator have been as high as 300 kw. at a current of 700 amperes. In another embodiment, an arcing passage lined with the same material, but one inch in diameter and six inches long has been provided. Power inputs into this generator have been as high as 2000 kw. at 3000 amperes.

In FIG. 4 we have shown an embodiment of our invention which utilizes an arcing passage of a flattened, generally rectangular cross section rather than the cylindrical cross section of FIG. 3. The shorter transverse dimension A of such a passageway is controlling in determining the Reynolds number of the flow in the passage. By keeping this dimension A relatively small and the transverse dimension B relatively large, we can limit the Reynolds number to a sufficiently low value to inhibit turbulence. This inhibition of turbulence serves the desirable function of making the arc more stable.

It has been found that our main jet 50 is exceptionally stable, i.e., free from fluctuations in temperature and velocity. This is believed to be due in large measure to the particular axial flow pattern that is followed by the two main streams of plasma as they travel down the arcing passage toward the exhaust port 22. This axial flow pattern is characterized by a high degree of freedom from transversely-directed components, such as vortex-type flow, and this is believed to materially inhibit fluctuations.

Another factor that inhibits these fluctuations is that the exhaust port 22 is located substantially midway between the electrodes 12. Thus, each of the two main streams flowing toward the exhaust port 22 has substantially the same velocity and flow rate, and the streams are therefore able to merge with less turbulence as they exhaust through ports 22.

The composition of the insulating liner 20 will determine the composition of the jet 50. For example, by using a liner of Delrin, which is E. I. du Pont Co.'s trademark for a plastic having a formula of $(CH_2O)_n$, we can obtain a jet consisting of carbon, hydrogen, and oxygen. As another example, by using a liner of methyl methacrylate, $(C_5H_8O_2)_n$, we can obtain a jet consisting of carbon, hydrogen, and oxygen, but in different proportions.

We can also derive our jet from materials normally occurring in the gaseous or liquid states. To do this, we solidify the normally-liquid or normally-gaseous material, converting it into a solid which has the shape of the liner 20. The resulting solid is then used in the same manner as the above-described liner 20. Examples of materials that can be handled in this manner are water, carbon dioxide, oxygen and nitrogen.

Because of the extremely high temperatures that can be obtained with our plasma generator, our plasma generator can be used to great advantage in spectro-chemical analysis. One way of doing this is to first pulverize the material that is to be analyzed, and then suitably imbed

it in the insulating material of liner 20. When the arc is formed, it decomposes this imbedded material along with the insulating wall. A spectro-chemical analysis of the extremely hot jet 50 can reveal properties of the test material that would have gone undetected at lower temperatures.

In connection with spectro-chemical analyzers, it is important to note that the plasma temperature can, by choice of arcing passage diameter, be regulated precisely and repetitively over a wide range of temperatures. Another significant feature is that with low currents, e.g. 50 amperes or even lower, very high temperatures (of up to 20,000° K.) can be developed, if only the diameter of the arcing passage is made small enough. Since such low currents are commonly available in laboratories, the versatility of our device in spectro-chemical analysis will be apparent.

Another advantage of our arc plasma generator is that it readily lends itself to operation at high pressures. All that is required is that the generator be located in a container pressurized to the desired extent. Available evidence indicates that operation at pressures as high as several hundred atmospheres is feasible.

While we have shown and described particular embodiments of our invention, it will be obvious to those skilled in the art that various changes and modifications may be made without departing from our invention in its broader aspects; and we, therefore, intend in the appended claims to cover all such changes and modifications as fall within the true spirit and scope of our invention.

What we claim as new and desire to secure by Letters Patent of the United States is:

1. An arc plasma generator comprising:
  - (a) a pair of electrodes between which an arc having its terminals located on said electrodes is adapted to be established,
  - (b) means defining an arcing passage extending between said electrodes for receiving the column of said arc,
  - (c) insulating material lining said arcing passage and directly exposed to said arc for evolving gases when heated by said arc, said gases being heated to a high temperature by said arc,
  - (d) means defining an exhaust passage communicating with said arcing passage and extending transversely thereof at a location intermediate said electrodes,
  - (e) means for forcing most of the gases evolved from said insulating material to flow along said arcing passage toward said exhaust passage and then out through said exhaust passage,
  - (f) scavenging means for substantially preventing the vapors evolved from each of said electrodes by said arc from entering the stream of gases flowing toward said exhaust passage,
  - (g) said scavenging means comprising means for causing a minor portion of the gases evolved from said insulating material by said arc to flow past each of said electrodes in a direction leading away from said exhaust passage.
2. The arc plasma generator of claim 1 in which:
  - (a) each of said electrodes is of a hollow configuration and has an arc terminal-receiving passage extending therethrough in general alignment with the portion of said arcing passage adjacent said electrode, and
  - (b) said scavenging means comprises means defining a restricted venting passage communicating with each of said arc-terminal receiving passages at the opposite side of said electrode from said arcing passage.
3. The arc plasma generator of claim 1 in which:
  - (a) each of said electrodes is of a hollow configuration and has an arc terminal-receiving passage extending therethrough in general alignment with the portion of said arcing passage adjacent said electrode,
  - (b) said scavenging means comprises means defining a restricted venting passage communicating with each

of said arc terminal-receiving passages at the opposite side of said electrode from said arcing passage, (c) and sealing means in the region adjacent the upstream surface of each of said hollow electrodes for blocking the escape of gases in a direction transversely of the arcing passage in said region.

4. The arc plasma generator of claim 1 in which said insulating material lining said arcing passage is a material that is a fluid at normal room temperature but is in a frozen, solid-state condition immediately before said arc is established.

5. A spectro-chemical analyzer comprising the arc plasma generator of claim 1, said insulating liner containing imbedded particles of the material that is to be analyzed.

6. The arc plasma generator of claim 1 in which said arcing passage has a transverse cross-sectional configuration characterized by a relatively small dimension in one direction and a relatively large dimension in a direction transverse to said one direction.

7. The arc plasma generator of claim 1 in which:

(a) each of said electrodes is of a hollow configuration and has an arc terminal-receiving passage extending therethrough in general alignment with the portion of said arcing passage adjacent said electrode,

(b) said scavenging means comprises means defining a restricted venting passage communicating with each of said arc-terminal receiving passages at the opposite side of said electrode from said arcing passage,

(c) each of said electrodes has a downstream surface facing said exhaust passage,

(d) and means is provided adjacent said downstream surface to normally prevent attachment of an arc terminal to said downstream surface.

8. The arc plasma generator of claim 1 in which said exhaust passage directly communicates with a space that is at a high pressure relative to normal atmospheric pressure.

9. An arc plasma generator comprising:

(a) a pair of electrodes between which an arc having its terminals located on said electrodes is adapted to be established,

(b) means defining an arcing passage extending between said electrodes for receiving the column of said arc,

(c) insulating material lining said arcing passage and directly exposed to said arc for evolving gases when heated by said arc, said gases being heated to a high temperature by said arc,

(d) means defining an exhaust passage communicating with said arcing passage and extending transversely thereof at a location intermediate said electrodes,

(e) said insulating material being a material that is a gas at normal room temperature but is in a frozen, solid-state condition immediately before said arc is established.
